UNITED STATES PATENT OFFICE.

JOHN ANDERSON, OF ST. LOUIS, MISSOURI, ASSIGNOR OF ONE-HALF TO
PATRICK H. CLARKE, OF SAME PLACE.

CAR-TRUCK.

SPECIFICATION forming part of Letters Patent No. 623,694, dated April 25, 1899.

Application filed September 19, 1898. Serial No. 691,377. (No model.)

To all whom it may concern:

Be it known that I, JOHN ANDERSON, a citizen of the United States, residing at St. Louis, in the State of Missouri, have invented certain new and useful Improvements in Car-Trucks, of which the following is a full, clear, and exact description, reference being had to the accompanying drawings, forming a part hereof.

10 My invention relates to improvements in car-trucks; and it consists in the novel combination and arrangement of parts, as will be hereinafter more particularly described, and pointed out in the claims.

15 In the drawings, Figure 1 is a combined side elevation and sectional view of my complete invention; and Fig. 2 is a top plan view of the same, showing one side of the truck.

The object of my invention is to construct 20 a car-truck more especially adapted for the electric motor which forms the subject-matter of another application, and embodies in its construction simplicity, durability, and the necessary yielding effect designed for a practical car-truck.

Briefly stated, the invention consists of side 25 members properly secured together by braces and adapted to contain the axle-boxes which form the bearings for the opposite ends of the axles of the track-wheels; cups or boxes forming a continuation of said bearings; a central pedestal; a plate forming the bottom of the same and having a U-shaped depending extension which coöperates with or is located between the intermediate side braces of the truck and operates as a guide for the vertical movement of the upper portion of the said truck; a bearing slidingly located within said pedestal and adapted to receive 30 the end of the armature-shaft of the electric motor; a spring interposed between the top of the pedestal and the upper surface of the said bearing, whereby the propelling disk or wheel which is fixed to the armature-shaft is 35 yieldingly held in frictional contact with the tread of the track-wheels; inverted cups adapted to receive or telescoping with the cups forming a continuation of the bearings which receive the ends of the axles of the 40 track-wheels; coiled springs interposed be-

tween said bearings and inverted cups, and angularly-arranged braces rigidly securing the last-named cups to the pedestal.

Referring to the drawings, 1 represents the side members of the truck, which are secured together by connecting-braces 2, the said side members adapted to removably receive the bearings 3, which form boxes for the opposite ends of the axles 4 of the track-wheels 5. Forming a continuation of the boxes 3 are 55 cup-shaped extensions 6, upon the bottom of which rest the lower ends of coiled springs 7, the latter being located within said cups, and inverted cups 8, which receive or telescope with the said cup-shaped extensions 6, and 60 the upper ends of the springs yieldingly supporting the upper portion of the truck, of which they form a part.

The upper or movable portion of the truck 9 is composed of a central hollow pedestal 10, 70 closed at its bottom by a plate 11, which is bolted or otherwise secured to the same and forming a continuation of said plate, and depending therefrom is a U-shaped extension 12, which is loosely received between the adjacent central connecting-braces 13 and operates as a guide for the vertical movement of the upper portion of the truck. Slidingly located within the pedestal 10 is a box 14, which forms a bearing for one end of the armature-shaft 15 of the electric motor, and also located within the said pedestal and interposed between the said box and the upper wall thereof is a coiled spring 16, which operates to hold the wheel or disk 17 in frictional contact with the tread portions of the track-wheels 5. The inverted cups 8 are rigidly secured to the pedestal 10 by means of angularly-arranged brace-plates 18, as clearly shown in Fig. 1, and upon said pedestal the 80 car-body is adapted to rest and be supported thereby.

The central side braces 13 of the truck are connected by a transverse beam 19, which extends from one side of the truck to the other and which operates to hold the parts comprising the lower portion of the truck rigidly together.

I do not limit myself to the precise construction and arrangement of parts as herein 90 100

shown and described, as it is evident that the same may be varied without departing from the nature of my invention.

In carrying out my invention the boxes 3 for the ends of the axles 4 are specially constructed for the present design of truck, and for this reason the bearing-plates 20 are located at the upper opposite corners of the box or at a point where the pressure and wear will 10 be the greatest.

Having fully described my invention, what I claim, and desire to secure by Letters Patent, is—

1. A car-truck comprising suitable side 15 members constituting the lower portion of the truck, boxes carried by said members forming bearings for the opposite ends of axles for the track-wheels, and a central pedestal yieldingly mounted upon the lower portion 20 of the truck upon which the car-body is adapted to rest, as and for the purpose described.

2. A car-truck comprising suitable side 25 members constituting the lower portion of the truck, boxes carried by said members forming bearings for the opposite ends of the axles for the track-wheels, a central pedestal upon which the car-body is adapted to rest, braces forming a rigid part of said pedestal 30 and extending on either side of the same, and spring interposed between the said braces and lower portion of the truck whereby the said pedestal is yieldingly mounted upon the said lower portion of the truck, as and for the purpose described.

3. A car-truck comprising a lower portion, cup-shaped extensions forming a part of the same, a central pedestal yieldingly mounted upon the said lower portion of the truck, inverted 40 cups located on either side of said pedestal and forming a rigid part of the same, and coiled springs located within said telescoping cups whereby the upper portion of the truck is yieldingly mounted upon the 45 lower portion of the same, as and for the purpose described.

4. A car-truck comprising a lower portion, cup-shaped extensions forming a part of the same, a hollow central pedestal, a removable bottom for the same, an extension forming a 50 part of the latter and coöperating with the lower portion of the truck, inverted cups adapted to telescope with the first-named cups and located on either side of the pedestal and forming a rigid part of the same, coiled 55 springs located within said cups, a box slidably located within said pedestal and adapted to receive the armature-shaft of an electric motor, and a coiled spring located within the said pedestal and interposed between the 60 top of the same and the box contained therein whereby the wheel or disk carried by the said armature-shaft is yieldingly held against the track-wheels, as and for the purpose described. 65

5. In a car-truck a box forming the bearing of the end of the axle of the track-wheel, and a bearing-plate forming a part of the said box and located at the upper corner of the same, as and for the purpose described. 70

6. A car-truck comprising a lower portion, boxes carried by the same, cup-shaped extensions forming a part of said boxes, a transverse beam connecting the opposite sides of said lower portion, a central pedestal upon 75 which the car-body is supported, a U-shaped extension depending from the bottom of said pedestal and coöperating with the central lower portion of the truck-frame, inverted cups telescoping with the said cup-shaped 80 extensions, coiled springs located within said cups, and angularly-arranged braces rigidly connecting the inverted cups to the opposite sides of the pedestal, as and for the purpose described. 85

In testimony whereof I affix my signature in presence of two witnesses.

JOHN ANDERSON.
